* cited by examiner

Primary Examiner — Cynthia M Chin(74) *Attorney, Agent, or Firm* — Gifford, Krass, Sprinkle, Anderson & Citkowski, P.C.; Mark D. Schneider(57) **CLAIM**

I claim the ornamental design for a toy projectile, as shown and described.

DESCRIPTION

FIG. 1 is a perspective view of a toy projectile according to the design, the portions shown in phantom forming no part of the design;

FIG. 2 is a side elevation view of the toy projectile according to the design, a corresponding opposing side plan view being a mirror image thereof, and the portions shown in phantom forming no part of the design;

FIG. 3 is a top plan view of the toy projectile according to the design; and,

FIG. 4 is a bottom plan view of the toy projectile according to the design, the portions shown in phantom forming no part of the design.
